US0D1112258S

(12) **United States Design Patent** (10) Patent No.: US D1,112,258 S
Ford et al. (45) Date of Patent: ** Feb. 10, 2026

- (54) **DISPLAY SCREEN OR PORTION THEREOF WITH A GRAPHICAL USER INTERFACE FOR DISPLAYING AGRICULTURAL DATA**

(71) Applicant: **CLIMATE LLC**, Saint Louis, MO (US)

(72) Inventors: **Zachary Ford**, Saint Ann, MO (US); **Philip Park**, Atlanta, GA (US); **Charlotte Schaefer**, Kirkwood, MO (US); **Nicholas Shwaery**, Miami, FL (US)

(73) Assignee: **Climate LLC**, Saint Louis, MO (US)

(**) Term: **15 Years**

(21) Appl. No.: **29/884,000**

(22) Filed: **Feb. 6, 2023**

CLAIM

The ornamental design for a display screen or portion thereof with a graphical user interface for displaying agricultural data, as shown and described.

DESCRIPTION

The file of this patent contains at least one drawing executed in color. Copies of this patent with color drawing(s) will be provided by the Office upon request and payment of the necessary fee.

FIG. 1 is a front view of a first embodiment of a display screen or portion thereof with a graphical user interface for displaying agricultural data in accordance with the claimed design.

FIG. 2 is a front view of a second embodiment of a display screen or portion thereof with a graphical user interface for displaying agricultural data in accordance with the claimed design; and

FIG. 3 is a front view of a third embodiment of a display screen or portion thereof with a graphical user interface for displaying agricultural data in accordance with the claimed design.

The outermost broken lines in the figures show a display screen or portion thereof, and form no part of the claimed design.
